UNITED STATES PATENT OFFICE.

NATHAN A. KURMAN, OF OAKLAND, CALIFORNIA, ASSIGNEE, BY MESNE ASSIGNMENTS,
TO INTERNATIONAL CALLOPHONE CORPORATION, OF NEW YORK, N. Y., A CORPO-
RATION OF DELAWARE.

SOUND TRANSMITTING AND REPRODUCING UNIT.

1,201,060.

Specification of Letters Patent. Patented Oct. 10, 1916.

Application filed May 9, 1913, Serial No. 766,630. Renewed May 18, 1916. Serial No. 98,439.

To all whom it may concern:

Be it known that I, NATHAN A. KURMAN, a citizen of the United States, residing at Oakland, in the county of Alameda and 5 State of California, have invented certain new and useful Improvements in Sound Transmitting and Reproducing Units, of which the following is a specification.

This invention relates to telephonic apparatus and has as its principal object the production of a combined unit adapted to act as both receiver and transmitter.

A second object of the invention is to produce a transmitter adapted to be actuated 15 by the voice of a person speaking in an ordinary tone anywhere within the room in which the instrument is situated.

A further object is to increase the range in volume of the previous receivers of the 20 loud speaking type.

The final object resides in the particular arrangement and combination of parts hereinafter described.

In the accompanying drawing:—Figure 1 25 is a central longitudinal cross sectional view taken through a combined transmitting and receiving unit embodying my improvement therein, and showing the same mounted in a horn. Fig. 2 is a section taken on line 30 2—2 of Fig. 1 looking in the direction of the arrow. Fig. 3 is a central vertical longitudinal section showing the operating parts of my combined receiving and transmitting unit and taken on the line 3—3 of Fig. 4. Fig. 4 35 is a cross sectional view taken on the line 4—4 of Fig. 3, looking in the direction of the arrow.

In the separate views the same part is 40 designated by the same reference character.

Referring more particularly to the drawing, my improved loud speaking receiver or sound reproducer comprises, as shown in Figs. 3 and 4, two permanent magnets 1—1 45 of horse shoe form held in place by clamps such as 2—2 preferably of soft iron, said clamps being attached to the magnets by means of screws such as 3—3. As clearly shown in Fig. 4, the magnets 1—1 are spaced apart and it will be understood that the screws 3—3 pass between and not into the magnets. At their inner ends the screws 3 50 are threaded and engage pole pieces such as 4—4 of which two are provided and which project toward each other from the inner

faces of the magnets. At their outer ends 55 the screws 3—3 pass through recesses in brass yokes such as 5—5, the purpose of which will hereinafter appear. A U-shaped soft iron core 6 is screwed to the yokes 5—5 intermediate thereof and is surrounded by a 60 coil 7 which is wound transversely to the plane of Fig. 3. The coil 7 is attached at its two ends to the binding posts 8—8 which extend through the box 9 in which the transmitting and receiving apparatus is mounted. 65 As shown clearly in Fig. 3, the separated edges of the channel shaped core 6 extend into the space between the two pole pieces 4—4 and almost to the horizontal line connecting the centers of said pole pieces. 70 Adjacent the ends of the core 6 and set approximately on said central line between the two pole pieces, is an armature 10 of soft iron. The armature 10 is connected to a membrane 11 by means of a bent arm such as 12. The 75 armature 10 is of soft iron but I have discovered that mica is the substance best adapted for use as the membrane 11, since it possesses great resiliency and its vibrations are of greater amplitude than those which 80 can be obtained from a diaphragm of soft iron or steel just as is ordinarily employed, and consequently the volume and clearness of tone given from the mica diaphragm is superior to that obtainable from previous 85 receivers or sound reproducers.

The edges of the diaphragm 11 are held between two ring like gaskets of oiled silk 12^a—12^a which gaskets 12^a—12^a are held between two casings 13 and 14, the casing 14 90 being somewhat dished and having a threaded tube 15 which projects through and has threaded engagement with the side of the casing 9. The casing 13 is also provided with a flange 16 which is interiorly screw 95 threaded and engages a flange on the casing 14. The casing 14 is of annular form and is supported from the magnets 1—1 by means of bolts 17—17 which extend through the space between the two magnets. 100

Now it will be understood that a magnetic field exists between the pole pieces 4—4 and that the armature 10 will tend to thread itself parallel to the direction of the magnetic field in which it is placed. Consequently, 105 when the field of the magnets 1—1 is not disturbed the armature 10 will occupy the position shown in Fig. 3 coinciding with

the central line joining the faces of the pole pieces 4-4. When, however, voice currents are imposed on the coil 7 a magnet field is set up around the edges of the core 7 which is in points substantially at right angles to the field due to the pole pieces 4-4. The armature 10 will tend to set itself parallel to the direction of the resulting magnetic field and consequently voice currents in the 10 coil 7 cause the armature 10 to vibrate causing a corresponding vibration of the diaphragm 11 with the production of speech.

As clearly shown in Fig. 4, the armature 10 is pivotally mounted by means of screws 15 18 which are mounted centrally in two non-magnetic bars 19 suitably supported at the ends of the flange 2.

Within the case 9 I provide also a sensitive transmitter comprising a casing 20 of 20 non-conducting material which is supported on the magnet 1 opposite the receiver by means of bolts such as 21-21, which pass between the magnets and carry nuts engaging a suitable yoke 22 of insulating material. The 25 interior of the casing 20 is hollowed out to receive a conducting member 23 preferably of graphite which is held within the casing 21 by means of a bolt such as 24. A ring 25 is threaded to the casing 20 as at 26 and 30 is provided with an inwardly projecting flange as shown at 27 adapted to clamp the diaphragm 28 against the edge of the casing 20. The ring 23 is also threaded as at 29 to receive the end of a cone shaped sound 35 collector 30 which is secured to the casing 9 by a suitable means, the casing being perforated as shown at 31 to permit the sound waves to have free access to the diaphragm 28. The diaphragm 28 is of steel treated 40 with a waterproof varnish. The chamber between the member 23 and the diaphragm 28 is half filled with granular carbon 32. Connections for the transmitter are made through binding posts 331-331, one of 45 which is connected to the central bolt 24 and the other to the ring 25.

The casing 9 is preferably placed within a horn such as 33^a and supported therein by any suitable means such as a spider 34 50 shown in Figs. 1 and 2. The horn 33^a is mounted in a supporting base or member 35 which is provided with a central aperture 36 through which wires for the transmitting and receiving members may be introduced.

55 As clearly shown in Fig. 1, I prefer to mount my combined receiving and transmitting element with the transmitter disposed toward the large end of the horn 33^a and I provide a small interior horn such as 37 which may be screw threaded to the tube 15 which directs the sound from the diaphragm 11 to the small curved surface at the rear of the horn 33^a from which it is reflected around the casing 9 without interference.

It will be understood that while I have shown and described the preferred form of my invention, various modifications and rearrangements thereof may be made without departing from the spirit of my invention, 70 and that parts thereof may be used without utilizing the whole.

Having thus described my invention, what I claim is:

1. In a telephone apparatus in combination, a diaphragm, a casing in which said diaphragm is suitably supported, a permanent magnet, an armature disposed in the field of said magnet, a connection between said diaphragm and said armature, a channel or U-shaped member of soft iron disposed with its edges adjacent said armature, and a receiving coil for energizing said channel member. 75

2. In a telephone apparatus in combination, a diaphragm, a casing in which said diaphragm is suitably supported, a permanent magnet, an armature disposed in the field of said magnet, a connection between said diaphragm and said armature, a channel or U-shaped member of soft iron disposed with its edges adjacent said armature, and a coil wound around said channel shaped member and having the wire therein disposed in planes extending transverse to 95 the direction of the magnetic force emanating from said magnet.

3. In a telephonic apparatus in combination, a horn, and a combined transmitting and receiving unit disposed within said 100 horn, said unit comprising a sensitive transmitter and a loud speaking receiver, said unit and said horn being so arranged that exterior sound waves entering said horn are guided to said transmitter and sound waves 105 admitted from said receiver are directed out of said horn.

4. In a telephonic apparatus in combination, a horn, and a combined transmitting and receiving unit disposed within said 110 horn, said unit comprising a sensitive transmitter and a loud speaking receiver, said unit being provided with an outer casing which is provided with oppositely placed 115 apertures one of which is directed toward the mouth of said horn and the other of which is directed toward the small closed end of the horn.

5. In a telephonic apparatus in combination, a horn, and a combined transmitting 120 and receiving unit supported within said horn intermediate the ends thereof, said unit being provided with an outer casing, said casing being provided with two oppositely disposed apertures, one of which faces the mouth of the horn and the other the closed end thereof, a sensitive transmitter disposed within said casing in communication with said first mentioned aperture, a 125 loud speaking receiver disposed within said 130

casing in communication with said second mentioned aperture, and a small horn extending from said second mentioned aperture to the small end of said first mentioned horn.

6. In a telephonic apparatus, in combination, a horn open at the large end and substantially closed at the other or small end, with a loud-speaking receiver arranged 10 within the horn to vibrate the air therein in a direction toward the closed end of the horn, and a sensitive transmitter also arranged within the horn and having its mouth piece directed outwardly toward the 15 open end of the horn, said horn acting to direct sound waves into the transmitter and to receive and amplify sound waves from the receiver.

7. In a telephonic apparatus, the combination of a horn open at one end and substantially closed at the other, with a sensitive transmitter having a diaphragm and a loud-speaking receiver having a diaphragm arranged within said horn and intermittent of its ends, the transmitter diaphragm having its surface receiving the sound waves directed toward the open end of the horn and the receiver diaphragm having its operative surface for producing sound waves directed toward the closed end of the horn. 25 30

In testimony whereof I affix my signature in the presence of two witnesses.

NATHAN A. KURMAN.
